(57) **CLAIM**

The ornamental design for a cutting insert, as shown and described.

DESCRIPTION

FIG. 1 is a top perspective view of the cutting insert showing our new design;

FIG. 2 is a bottom perspective view thereof;

FIG. 3 is a top view thereof;

FIG. 4 is a bottom view thereof; and,

FIG. 5 is a front view thereof, with left side, right side, and rear views being identical to the front view.

The cutting insert is rotationally symmetrical 90 degrees around a central axis thereof.

The broken lines depict portions of the cutting insert in which the design is embodied and form no part of the claimed design.
